UNITED STATES PATENT OFFICE.

MARVIN O. DISCHER, OF MOBILE, ALABAMA.

DESIGN FOR AN EMBLEM OR FOB-JEWEL.

No. 39,873.

Specification for Design.

Patented March 16, 1909.

Application filed December 18, 1908. Serial No. 468,239. Term of patent 7 years.

To all whom it may concern:

Be it known that I, MARVIN O. DISCHER, a citizen of the United States, residing at Mobile, in the county of Mobile and State of Alabama, have invented a new, original, and ornamental Design for Emblems or Fob-Jewels, of which the following is a specification, reference being had to the accompanying drawing, forming part thereof.

Figure 1 is a face view of an emblem or fob-jewel, showing my new design. Fig. 2 is a view of the obverse side.

I claim:

The ornamental design for an emblem or fob-jewel, as shown.

MARVIN O. DISCHER.
